UNITED STATES PATENT OFFICE.

CHARLES B. SMITH, OF FITCHBURG, MASSACHUSETTS.

DESIGN FOR FABRIC.

SPECIFICATION forming part of Design No. 18,347, dated May 22, 1888.

Application filed April 13, 1888. Serial No. 270,597. Term of patent 3½ years.

To all whom it may concern:

Be it known that I, CHARLES B. SMITH, of Fitchburg, in the county of Worcester and State of Massachusetts, have invented and produced a new and original Design for Fabric, of which the following is a full, clear, and exact specification.

My new design is fully illustrated in the accompanying photograph, to which reference is made.

a a represent stripes of equal width, and *b b* stripes alternating the stripes *a* and of equal width therewith. The stripes *a* show diagonal ribs *a'*, comprised of a succession of short lines,

a', parallel with the line of the length of the stripes *a*. The stripes *b* are composed of several parallel narrow ribs, *b'*, composed of a succession of short transverse lines, *b''*.

I claim—

The design for fabric herein shown and described, the same consisting of the stripes *a a*, ribs *a'*, crossing the stripes *a* diagonally, and the alternating stripes *b b*, showing parallel ribs *b''*.

CHARLES B. SMITH.
